CLAMP

Max Laube, Minneapolis, Minn., assignor to The
L. S. Starrett Company, Athol, Mass., a corpora-
tion of Massachusetts

Application January 26, 1948, Serial No. 4,264

2 Claims. (Cl. 248—226)

1

This invention relates to clamps and more particularly to a clamp for holding a dial test indicator in operative position relative to the work to be tested.

As presently constructed, such clamp consists of a C-shaped frame, one arm of which terminates in a head provided with an opening to receive the threaded end of the post or arm which carries the dial indicator, and the other arm of which provides a bearing for the clamp screw. In this construction the post or arm is coaxial with the clamp screw and hence the use of the dial indicator is limited to positions where the clamp can be mounted on the lathe or other surface with its post or arm sufficiently close to the work to enable the contact plunger of the dial indicator to contact the work.

In order to avoid this limitation it has been proposed (Patent No. 2,371,451) to provide the clamp head with a plurality of tapped holes, spaced 90° apart, within which the indicator supporting post or arm may be selectively mounted. One objection to such multiple socket head however, is that it provides for only four positions of adjustment of the supporting post or arm. Another objection is that the post or arm can be changed from one position to another only by unscrewing it from one tapped hole and screwing it into another hole.

The main object of my present invention is to provide a clamp in which the indicator post or arm is capable of being adjusted to and locked in a multiplicity of positions amounting to a universal range of adjustment with reference to the clamp.

Another object is to provide a clamp in which the indicator post or arm is always connected to the clamp regardless of the position to which it is adjusted.

A further object is to provide a clamp which is simple in design, inexpensive of manufacture, and convenient to operate.

Other objects and advantages will appear as this description proceeds, and in the accompanying drawing wherein I have disclosed a preferred embodiment of my invention:

Figure 1 is a side elevation of my novel clamp applied to a suitable support and equipped with a conventional dial indicator, and showing in full and dotted lines several of the numerous positions into which the dial indicator may be adjusted and locked when the supporting post or arm is swung about a horizontal axis through a full circle.

Figure 2 is a plan view of Figure 1, and show-

ing in full and dotted lines two of the numerous positions the post or arm may assume when swung about a vertical axis through a full circle.

Figure 3 is an enlarged section on the line 3—3 of Figure 2 and showing in full and dotted lines several of the many positions which the supporting post or arm may assume when swung about a horizontal axis, and

Figure 4 is a section on the line 4—4 of Figure 3.

The frame of my novel clamp is C-shaped, and comprises a body 10 which terminates at its ends in spaced horizontal arms 12 and 14. Arm 14 serves as a bearing for a threaded clamp screw 16 between the head of which and the arm 12 the bench or other support indicated at A is adapted to be clamped.

Body 10 is bored and counterbored from end to end as shown in Figure 3 to receive a rotatable stem 20 of greater length than said body. The lower end of said stem projects beyond the end of body 10 and is threaded to receive an adjusting nut 18, body 10 adjacent its lower end being counterbored to receive a coil spring 26 which reacts between the shoulder at the inner end of said counterbore and a washer 28 clamped against the outer face of body 10 by said nut.

Fast to the upper end of stem 20 is a split head 30, the lower face of which is formed as a conical bearing surface 32 which projects into a conical bearing surface 34 formed in the outer face of said body at the upper end thereof. Head 30 is made fast to the upper end of stem 20 in any suitable manner. As here shown, the upper face of head 30 is recessed to receive a locking collar 22 pinned to stem 20 as at 24. Head 30 is formed with an offset bearing portion 31 having a horizontal bore connecting with the split thereof within which bore is rotatively mounted the bent inner end 40' of a dial indicator supporting post 40. The end 40' of post 40 is relatively short and is bent at substantially right angles to the post. It is secured within said bore in any suitable manner, as by tapping and threading it to receive a

clamping screw 44, there being a washer 42 clamped between the head of said screw and the adjacent face of the offset portion 31 of said head. At its free end post 40 is adapted to be detachably fastened in any suitable manner to the back of a conventional dial indicator 46 having a work contact plunger 48.

When nut 18 is tightened, it initiates a double clamping action. Portion 32 of head 30 is drawn tightly against its seat 34 on body 10 to lock the head against rotation about a vertical axis and

simultaneously the split sections of the head are drawn together to cause the bore in offset 31 to clamp the end 40' of post 40 against rotation about a horizontal axis.

When said nut is loosened, the post may be adjusted to a multiplicity of positions by either rotating head 30 about a vertical axis or rotating the post itself about a horizontal axis within the bearing 31 of said head.

While I have described and illustrated a preferred embodiment of my invention, it is to be understood that the same may be variously changed within the scope of the appended claims.

Having thus described my invention, what I claim as new and desire to secure by Letters Patent is:

1. A gauge supporting device comprising a body having a bore therethrough, a head on the body at one end of the bore and having a bore therethrough disposed laterally of and right angular to the first named bore, a gauge supporting post having one end portion disposed in the second named bore and the other end portion disposed relatively angular thereto, the head being adjustable on the body about the axis of the first named bore and the post being adjustable in the head about the axis of the second named bore, and means including a rod in the first named

bore for simultaneously clamping the head and post against said adjustments.

5 2. The gauge supporting device defined in claim 1 in which said head is a U-shaped clamp having two connected legs in superposed relation on the head and said second named bore is disposed therein at the junction ends of the two legs, said means including the rod extending through said legs and an element operative on

10 the rod to draw the legs into clamping engagement with the post and the head into clamping contact with the body.

MAX LAUBE.
